UNITED STATES PATENT OFFICE.

CONRAD C. BRACK, OF DETROIT, MICHIGAN.

DESIGN FOR A CHARM, STICK-PIN, OR SIMILAR ARTICLE.

48,745.

Specification for Design.

Patented Mar. 21, 1916.

Application filed October 25, 1915. Serial No. 57,889. Term of patent 7 years.

To all whom it may concern:

Be it known that I, CONRAD C. BRACK, a citizen of the United States, residing at Detroit, in the county of Wayne and State of Michigan, have invented a new, original, and ornamental Design for a Charm, Stick-Pin, or Similar Article, of which the following is a specification, reference being had to the accompanying drawing, forming a part thereof.

The figure is a plan view of a stick pin, showing my new design.

I claim:

The ornamental design for a charm, stick pin or similar article, as shown.

CONRAD C. BRACK.

Witnesses:

B. D. YORK,

RUSSELL A. HART.
